HARRY SCHINDELHEIM, OF BROOKLYN, NEW YORK

ATTACHMENT FOR HEMSTITCHING MACHINES

Application filed February 13, 1928. Serial No. 254,122.

This invention relates to fancy stitching machines and has particular reference to an attachment for two-needle hemstitching machines for producing a zigzag hemstitch pattern which has heretofore been produced only by hand.

While two-needle hemstitching machines have been in use for a considerable period of time, no attachment has heretofore been devised for producing a zigzag hemstitch pattern by machine and it is therefore an object of the present invention to provide means as an attachment for the usual two-needle hemstitching machine for producing a zigzag hemstitch pattern.

More specifically the invention comprehends in a two-needle hemstitching machine means for supporting the needles to dispose one in advance of the other and a bifurcated plunger having the furcations correspondingly disposed one in advance of the other to co-operate with the drawn portion of the material for separating the threads in a zigzag manner while the needles perform the stitching operation in the usual manner to retain the threads thus separated.

The invention furthermore comprehends an attachment of the character set forth which is simple in its construction and mode of use, inexpensive to manufacture, readily applicable to and removable from a machine, and which is highly efficient in its purpose.

With the above recited and other objects in view, reference is had to the following description and accompanying drawings in which there is exhibited one example of embodiment of the invention while the appended claims define the actual scope of the invention.

40 In the drawings—

Figure 1 is a perspective view of a two-needle hemstitching machine equipped with a plunger for producing a zigzag hemstitch pattern;

45 Fig. 2 is a fragmentary cross-sectional view taken approximately on the line indicated at 2—2 in Fig. 3;

50 Fig. 3 is a horizontal sectional view taken approximately on the line indicated at 3—3 in Fig. 2;

Fig. 4 is a side view of the plunger removed from the plunger bracket.

In carrying the invention into practice, the attachment is shown as applied to a Singer two-needle hemstitching machine commonly known as the 17—W type of machine, which is provided with a presser foot A, a plunger bar B, and which carries a pair of needles C mounted for vertical reciprocation. The plunger bar carries a bracket D which is mounted for vertical reciprocation with the plunger bar and which is apertured to receive the shank of a plunger or spreader for separating the threads E of the drawn portion of the material F where the hemstitch pattern is to be produced.

In the present invention the needles C are mounted so that one is slightly in advance of the other, a distance equal substantially to one-half the distance the material is fed by the feeding mechanism of the machine, it being of course understood that the same are transversely or laterally separated or spaced apart. The plunger for producing the zigzag hemstitch pattern includes a shank 10 having a bifurcated head 11, the furcations 12 and 13 of which are spaced apart laterally while the same are disposed one slightly in advance of the other corresponding to the arrangement of the needles C. In horizontal cross section the furcations are substantially crescent shaped and reversely arranged so that needle clearance grooves 14 and 15 are formed respectively on the outer side edges while the inner faces 16 and 17 are convex. The lower ends 18 and 19 of the furcations are pointed. The shank 10 is received in the apertured portion of the plunger bracket D and is secured thereto by a set screw G in the usual manner.

55 In use and operation when the plunger moves downwardly, the pointed lower terminals or ends 18 and 19 drive through the threads E of the drawn portion of the material F to separate the same in a zigzag manner as illustrated clearly in Fig. 3 of the drawings. The needles C cause the threads H to accomplish the usual form of chain stitch for securing the threads E of the drawn portion in their zigzag separated con-

dition, thereby producing the zigzag hemstitch pattern.

What is claimed is:

1. In a two-needle hemstitching machine, 5 a pair of needles supported in laterally spaced relation with one in advance of the other in the direction of the feed of the material through the machine a distance equal substantially to one-half the distance the material is fed by the feeding mechanism of the machine and a bifurcated plunger having furcations and of cross sectionally tapering shape inwardly from the outer sides, and said furcations being correspondingly disposed one in advance of the other and in laterally spaced 70 relation and adjacent the needles, for separating into and temporarily holding the threads of the drawn portion of the material in groups disposed at an angle to each other and an angle to the normal lie of the threads, whereby the needles may function to form stitching for securing the threads in the grouped relation specified.
2. In a two-needle hemstitching machine, 20 an attachment for producing a zigzag hemstitch pattern in a textile material having a drawn portion, said attachment including a pair of needles supported in laterally spaced relation with one in advance of the other in the direction of the feed of the material through the machine a distance equal substantially to one-half the distance the material is fed by the feeding mechanism of the machine and means to engage with, spread 30 and hold the threads of the drawn portion of the material in a zigzag manner, whereby the needles function to form stitching for permanently securing said threads in said zigzag fashion.
3. In a two-needle hemstitching machine, 35 an attachment for producing in a textile material having a drawn portion, a zigzag hemstitch pattern, said attachment including a pair of needles supported in laterally spaced relation with one in advance of the other in the direction of the feed of the material through the machine a distance equal substantially to one-half the distance the material is fed by the feeding mechanism of the machine and means to engage with, spread 40 and hold the threads of the drawn portion of the material in a zigzag manner, whereby the needles function to form stitching for permanently securing said threads in their zigzag arrangement.
4. In a two-needle hemstitching machine, 45 an attachment for producing in a textile material having a drawn portion, a zigzag hemstitch pattern, said attachment including a pair of needles supported in laterally spaced relation with one in advance of the other in the direction of the feed of the material through the machine a distance equal substantially to one-half the distance the material is fed by the feeding mechanism of the machine and means to engage with the threads of the drawn portion of the material to dispose the same in groups at an angle to each other and to the normal lie of the threads, said means being disposed in a corresponding relation to the needles and adjacent thereto, whereby said needles function to produce stitching for permanently securing the threads in the manner in which they are grouped by said means.
5. The combination with a two-needle hemstitching machine, of an attachment for producing in a textile material having a drawn portion, a zigzag hemstitch pattern, said attachment including a pair of needles, means for supporting said needles to dispose the 60 same in laterally spaced relation with one in advance of the other in the direction of the feed of the machine a distance equal substantially to one-half the distance the material is fed by the feeding mechanism of the machine and a bifurcated plunger having furcations and of cross sectionally tapering shape inwardly from the outer sides, and said furcations being correspondingly disposed one in advance of the other and in laterally spaced 75 relation and adjacent the needles, for separating into and temporarily holding the threads of the drawn portion of the material in groups disposed at an angle to each other and an angle to the normal lie of the threads, whereby the needles may function to form stitching for securing the threads in the grouped relation specified.

5. The combination with a two-needle hemstitching machine, of an attachment for producing in a textile material having a drawn portion, a zigzag hemstitch pattern, said attachment including a pair of needles, means for supporting said needles to dispose the same in laterally spaced relation with one in advance of the other in the direction of the feed of the machine a distance equal substantially to one-half the distance the material is fed by the feeding mechanism of the machine and a bifurcated plunger having laterally and inwardly cross sectionally tapered furcations correspondingly disposed one in advance of the other and in laterally spaced relation and adjacent the needles, for separating into and temporarily holding the threads of the drawn portion of the material in groups disposed at an angle to each other and an angle to the normal lie of the threads, whereby the needles may function to form stitching for securing the threads in the grouped relation specified, the said functions each having a longitudinal groove in the outer face thereof within which the needles are moved.

6. The combination with a two-needle hemstitching machine, of an attachment for producing in a textile material having a drawn portion, a zigzag hemstitch pattern, said attachment including a pair of needles, means for supporting said needles to dispose the same in laterally spaced relation with one in advance of the other in the direction of the feed of the machine a distance equal substantially to one-half the distance the material is fed by the feeding mechanism of the machine and a bifurcated plunger having furcations correspondingly disposed one in advance of the other and in laterally spaced relation and adjacent the needles, for separating into and temporarily holding the threads of the drawn portion of the material in groups disposed at an angle to each other and an angle to the normal lie of the threads, whereby the needles may function to form stitching for securing the threads in the grouped relation specified.

grouped relation specified, the said furcations being of substantially crescent shaped cross sectional configuration and each presenting a convex inner surface and a concave outer surface, which latter concave outer surface defines a needle groove within which the needle moves.

5 Signed at New York, in the county of New York, and State of New York, this 10th day
10 of February A. D. 1928.
